UNITED STATES PATENT OFFICE

EDWIN S. BOSSLER, OF JOHNSTOWN, PENNSYLVANIA

SWITCH-OPERATING MECHANISM

Application filed June 18, 1930. Serial No. 462,344.

This invention relates to switch operating mechanism and more particularly to the tongue-operating mechanism of switches used as part of the equipment of street railways.

The present invention contemplates the provision of a novel and greatly simplified form of mechanism to replace the spring link or toggle tongue-operating mechanism commonly used in switch boxes of the type illustrated and described in Patent No. 1,125,957, issued to Carroll Burton on January 26th, 1915.

In the drawings:

Figure 1 is a plan of switch operating mechanism embodying the features of the invention.

Figure 2 is a sectional view taken on the line II-II of Figure 1.

The reference numeral 5 designates the base frame or body of a tongue switch adapted for use on street railways and provided in its upper face with a longitudinal recess 6 in which the switch tongue 7 is mounted or positioned. In the particular construction shown the tongue 7 is pivoted at its heel on one end in the recess 6 and the switch point on the opposite end of the tongue is arranged to swing sidewise from one side to the other of the said recess against the sides 8 and 9 thereof.

Secured on one side of the frame or body 5 by means of bolts 10 is a switch box 12 normally provided with a lid or cover 13 but which, in Figure 1, is shown as removed, the box 12 being provided with ribs or flanges 14 for supporting said lid.

Projecting downwardly from the lower surface of the switch tongue 7 within recess 6 to a point below the bottom of the recess 6 is an integral lug 16 having a transverse opening therein in which one end of an adjustable reach-rod 17 is secure by a nut 18. The opposite end of the rod 17 is enlarged in diameter, a thimble or sleeve 19 being positioned on the reduced portion of said rod to provide a separator which serves to hold the rod rigidly in position on the lug 16 when nut 18 is screwed in place. The length of the thimble or sleeve 19 may be varied to suit the particular dimension of switch to which the

improved structure may be applied and in changing the switch to a single or double throw switch.

The enlarged end of the reach rod 17 is provided with an internally threaded axial opening in which the threaded end of a rod extension 20 is secured as by nut 21 and lock nut 22 so as to be adjustable to vary the overall length of the rod 17 and its extension. The extension 20 is provided with an enlarged flattened head 23 which is formed with a recess 24 for a purpose which will now be described.

The features of the present invention reside in the provision of means in the form of a compression spring 25 for yieldingly holding the switch tongue 7 against either of the opposite sides 8 and 9 of the recess 6, depending upon the position into which it may be desired to move the switch tongue and the manner in which the switch operating mechanism is adjusted.

This spring 25, as herein shown, is of the ribbon type and is seated at opposite extremities in recesses or seats 26 formed by lugs 27 which may be made integral with the side walls of the box 12, and at an intermediate point said spring is flattened over a predetermined portion of its length as at 25a and passed through the recess 24 of the head 23. The seats or recesses 26 which receive the opposite ends of the spring 25 are located substantially in an axial line with the neutral position of said spring, or the position thereof when on dead center and under greatest compression, and the flattened portion 25a is of such length as will permit a certain amount of relative movement between the spring and reach rod 17 due to a slight arc swing of the rod perpendicular to the movement of the tongue, the recess 24 being of such size as to permit such relative movement.

The operation of a switch equipped with the present form of throw or operating mechanism will be readily understood. When the switch tongue 7 is shifted from one side to the other of the recess 6, the reach rod 17 is correspondingly moved. At the beginning of this movement, the spring 25 is compressed until the neutral or dead center po-

5 sition of the spring is reached, and upon continued movement the spring passes dead center and the tongue is snapped over against the opposite side of the recess 6, at which time the spring will be in the position shown in dotted lines in Fig. 1.

10 As will be understood, the spring 25 should be of such strength as will permit efficient functioning of the mechanism. The simplicity of the device and the fact that it replaces a number of operating parts which are relatively expensive to produce affords a great advantage over prior forms of switch operating mechanism. Furthermore, the 15 spring will last almost indefinitely without getting out of order, a condition which is not present where relatively movable, frictional operating parts are used in an assembly for operating switches.

20 I claim:

25 1. In a switch a tongue, a reach rod connected at one extremity to said tongue and at its opposite extremity formed with a recess, and means for positioning said tongue comprising a compression spring formed intermediate of its length with a flattened portion which is movably positioned in said recess and seated at opposite extremities in an axial plane parallel with the longitudinal axis of 30 the spring when under greatest compression.

35 2. In a switch a tongue, a reach rod rigidly connected at one end to said tongue, and means for positioning said tongue comprising a compression spring held against expansion movement at its opposite ends and operatively connected at an intermediate point to said rod, the connection being such that relative movement is permitted between the 40 rod and spring to accommodate arcuate movement of said rod.

45 3. In a switch a tongue, a reach rod rigidly connected at one end to said tongue and at its opposite end formed with a recess, and means for positioning said tongue comprising a spring which is held against expansion movement at opposite ends and formed with a flattened portion intermediate its length which is slidingly positioned in said recess.

50 In testimony whereof, I have hereunto set my hand.

EDWIN S. BOSSLER.
